UNITED STATES PATENT OFFICE.

GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

BUTTONHOLE-SEWING MACHINE.

1,231,890.

Specification of Letters Patent.

Patented July 3, 1917.

Application filed April 26, 1916. Serial No. 93,608.

To all whom it may concern:

Be it known that I, GEORGE S. HILL, a citizen of the United States, residing at Strafford, in the county of Strafford and State of New Hampshire, have invented certain new and useful Improvements in Buttonhole-Sewing Machines; and I do hereby declare the following to be a full, clear, and exact description of the invention, such as will enable others skilled in the art to which it appertains to make and use the same.

The invention relates to buttonhole sewing machines, and more particularly to mechanism for operating the thread tension of such machines.

In sewing machines of this class, and particularly in machines which are provided with devices for holding the end of the needle thread at the beginning of the sewing, it is desirable, if not essential, that the application of the tension of the thread at the beginning of the seam be delayed until after the completion of the first stitch, as otherwise the end of the thread is liable to be pulled from the thread holder during the first cycle of the stitching mechanism, and before its end is properly anchored in the seam. It is accordingly the object of the present invention to provide novel and improved mechanism which will so control the application of the tension that it will be applied at a substantially uniform time in the second cycle of the stitching mechanism, irrespective of any variations in the relative speeds of the stitching and feed mechanisms incident to changes in the number of stitches to be made in the buttonholes.

To this end the invention comprises the features of construction and combinations of parts hereinafter described and referred to in the claims, the advantages of which will be understood by those skilled in the art from the following detailed description of a mechanism embodying the preferred form of the invention.

In the drawings, Figure 1 is a side elevation of a buttonhole making machine embodying the invention in its preferred form; Fig. 2 is a partial plan view of the machine; Fig. 3 is a partial sectional elevation on line 3, Fig. 2; and Fig. 4 is a detail sectional view on line 4, Fig. 2.

In the drawings the invention is shown as embodied in a buttonhole making machine having the construction and mode of

operation of the machine shown and described in Patent No. 1,063,880, June 3, 1913, and provided with a thread cutting and holding device such as shown and described in Patent No. 1,094,896, April 28, 1914. In this machine the stitching mechanism comprises an upper reciprocating needle 2 and supplemental under thread mechanism (not shown) driven through a shaft 4 which makes one revolution for each cycle of the stitching mechanism. The feed mechanism through which the work clamp and stitching mechanism are relatively moved during the sewing to form over-seam stitches about the buttonhole includes a cam gear 6 which makes one revolution during the making of a buttonhole. The feed mechanism is driven during the sewing from the stitching mechanism through gearing indicated at 8 which connects the shaft 4 with the gear 6, and which is so constructed that it may be readily changed to vary the speed of the cam gear with relation to the stitching mechanism, in accordance with the number of stitches which are to be made in sewing about the buttonhole. The machine is provided with a thread cutting and holding device indicated at 10, which is operated at the completion of the sewing to cut and hold the upper needle thread, and which retains the end of the thread until the initial stitches have been formed at the beginning of the next succeeding sewing operation, the thread holder and cutter being operated by cams on the feed cam gear 6, as fully described in Patent No. 1,094,896. The upper needle thread, on its way from the thread supply to the needle, passes through a tension device comprising the lower fixed disk 12 and the upper spring-pressed movable disk 14. The tension device is controlled to apply or release the tension through a tension releasing rod 16, the lower end of which rides on a cam 18 secured to the upper face of the cam gear 6, and the upper end of which carries a laterally projecting arm 20. The rear end of the arm 20 supports a pin 22 which extends downward from a plate 24 interposed between the spring and the tension disk 14. At the completion of the sewing the tension release cam 18 passes under the rod 16, raising the rod and thus releasing the tension. At the beginning of the sewing the cam 18 passes from under the rod 16, so that it may drop to apply the

tension. As thus far described, the machine is substantially the same in construction and mode of operation as the machine shown and described in the two patents above referred to.

In embodying the present invention in the above machine, it is preferred to retain the tension releasing cam and rod 16, and to provide means for controlling the application of the tension at the beginning of the sewing from the sewing mechanism, so that the tension will be applied at a uniform time in the stitch forming cycle, irrespective of variations in the extent of the movement imparted to the feed mechanism for each stitch forming cycle. In its preferred form this means consists of latching means which retains the tension in position of release, in case the movement imparted to the feed mechanism during the first stitch forming cycle is sufficient to carry the tension release cam 18 from beneath the rod 16, and which is tripped by the stitching mechanism to allow the tension to be applied at the proper time in the second stitch forming cycle. As shown, the latching means comprises a latch lever 26 provided with a vertical arm arranged to underlie the arm 20 of the tension release rod when the rod is in tension releasing position, and also provided with a horizontal arm arranged to be engaged by a cam or tappet carried by the shaft 4. The latch lever is forced yieldingly toward latching position by a spring 28. It is preferred to so arrange the horizontal arm of the latch lever that it will ride on the crank arm 30 through which the under thread mechanism is operated, the crank arm in such case acting as the cam or tappet for timing the application of the tension. It is to be understood, however, that the lever may be otherwise arranged, and may be tripped by any suitable cam or tappet secured to or carried by the shaft 4 and arranged or adjusted to trip the latch and apply the tension at the desired time in the stitch forming cycle.

With the construction shown, the tension release rod 16 will be raised at the end of the sewing by the cam 18 to release the tension, and the latch lever 26 will immediately swing into position to support the rod in tension releasing position, the shaft 4 being stopped at the completion of the sewing, in the position indicated in the drawings. At the beginning of the next succeeding sewing operation the lever 26 will be swung about its pivot by the crank arm 30 during the first downward stroke of the needle 2, but at this time the cam 18 will still underlie the end of the rod 16, and will retain the rod in tension releasing position. The latch lever will be immediately returned to active position beneath the arm 20 of the tension releasing rod, and in case the

end of the cam 18 passes from under the end of the rod, the latch will retain the rod in tension releasing position until the latch is tripped to release the rod by the engagement of the crank arm 30 with the latch lever during the second stroke of the needle. The application of the tension at the beginning of the sewing will therefore be accurately timed to take place at the proper time in the second stitch forming cycle, irrespective of the number of stitches to be made in the buttonhole, and of the rate of movement of the feed mechanism during each stitch forming cycle.

While it is preferred to employ the specific construction and arrangement of parts shown and described, in embodying the invention in the machine of the patents above referred to, it will be understood that this construction and arrangement is not essential to the broader features of the invention, and may be varied or modified as found desirable or best suited to the construction and arrangement of the parts of the machine in which the invention is to be embodied.

Having explained the nature and object of the invention, and specifically described one form of mechanism in which it may be embodied, what is claimed is:

1. A buttonhole sewing machine, having, in combination, stitching mechanism, feed mechanism, driving connections between the stitching mechanism and feed mechanism, means for applying tension to the thread at the beginning of the sewing controlled from the feed mechanism, and means for controlling the application of the tension from the sewing mechanism.

2. A buttonhole sewing machine, having, in combination, stitching mechanism, a thread holder, a tension device, feed mechanism, driving connections between the stitching mechanism and feed mechanism having provision for varying the speed of the feed mechanism with relation to the stitching mechanism, means for controlling the tension device from the feed mechanism, and means operated from the sewing mechanism for preventing premature application of the tension at the beginning of the sewing.

3. A buttonhole sewing machine, having, in combination, stitching mechanism comprising a reciprocating needle, feed mechanism for relatively feeding the work and stitching mechanism to sew about a buttonhole, a tension device, means operated from the feed mechanism for preventing application of the tension during the first stroke of the needle, and means operated from the sewing mechanism for applying the tension during the second cycle of the sewing mechanism.

4. A buttonhole sewing machine, having, in combination, stitching mechanism com-

prising a reciprocating needle, a tension device for the needle thread, means for preventing the application of the tension during the first stroke of the needle at the beginning of the sewing, and means operated from the sewing mechanism for applying the tension during the second cycle of the stitching mechanism.

5. A buttonhole sewing machine, having, in combination, stitching mechanism, feed mechanism, a tension device, means for releasing the tension at the completion of the sewing, means for latching the tension in position of release, and means operated by the stitching mechanism for tripping the latching means to apply the tension.

6. A buttonhole sewing machine, having, in combination, stitching mechanism, a tension device, feed mechanism provided with a tension release cam, means for latching the tension in position of release, and means operated by the stitching mechanism for tripping the latching means to apply the tension.

25 7. A buttonhole sewing machine, having,

in combination, stitching mechanism comprising an upper reciprocating needle, feed mechanism for relatively feeding the work and stitching mechanism to sew about a buttonhole, a thread holder for holding the thread at the beginning of the sewing, a tension device, means for controlling the application of the tension from the feed mechanism, and means for timing the application of the tension from the stitching mechanism.

8. A buttonhole sewing machine, having, in combination, stitching mechanism comprising a reciprocating needle, a tension device for the needle thread, means for releasing the tension at the completion of the sewing, means for latching the tension in position of release, means for tripping the latching means during each stitch forming cycle, and means for preventing the application of the tension when the latching means is tripped during the first stitch forming cycle.

GEORGE S. HILL.
